DESIGN FOR A COMPACT

Ora R. Sebastian, Shreveport, La.

Application March 3, 1936, Serial No. 61,462

Term of patent 14 years

To all whom it may concern:

Be it known that I, Ora R. Sebastian, a citizen of the United States, residing at Shreveport, in the Parish of Caddo and State of Louisiana, have invented a new, original, and ornamental Design for a Compact, of which the following is a specification, reference being had to the accompanying drawing, forming part thereof.

I claim:—

The ornamental design for a compact as shown.

ORA R. SEBASTIAN.
